COMBUSTION APPARATUS FOR FURNACES

William Ferguson, Philadelphia, Pa., assignor to
 National Airoil Burner Company, Incorporated,
 Philadelphia, Pa., a corporation of Delaware

Application August 22, 1950, Serial No. 180,738

2 Claims. (Cl. 158—1)

1

This invention relates to combustion apparatus for furnaces.

It has heretofore been proposed to provide center and single wall up-draft heaters, particularly for use in petroleum refinery processes, and in other heating processes where a substantial portion of the fuel heat is to be absorbed from flame radiation.

It has heretofore been proposed to provide alternative provisions for heating with oil or with gas firing, and one suitable form of apparatus for this purpose is shown in my prior United States Patent No. 2,512,319.

In a petroleum process furnace, it is not necessary to change either frequently, or rapidly, from oil to gas, or vice versa. In certain types of operation, oil is employed as a fuel only for bringing a cold furnace up to process temperature, after which a by-product gas from the process is available as fuel.

In other instances, natural gas may be obtained during certain seasons of the year, and it is only necessary to employ oil during part of the year, such as during a portion of the winter season. It is desirable, however, that provision be made for changing from one fuel to another without discontinuing the process.

It is the principal object of the present invention, therefore, to provide a furnace, and combustion apparatus therefor, which is simple in construction and which may be readily employed, as desired, for the combustion of gaseous fuel or oil, upon changing of the burners.

It is a further object of the present invention to provide improved combustion apparatus in which suitable provisions are made, in the furnace, for burning gaseous fuel or oil and with substantially the same flame pattern with either type of fuel.

It is a further object of the present invention to provide an improved furnace, and burner construction therefor, in which a plurality of air passageways are included, one for primary air and one for secondary air, and in which the burner, of desired type for the fuel to be burned, is removably mounted in the primary air passageway.

It is a further object of the present invention to provide an improved furnace, and burner construction therefor, in which provisions are made for preventing the admixture of spent combustion gases with the flame, thereby enhancing the character of combustion.

It is a further object of the present invention to provide an improved furnace, and burner construction therefor, in which the angle of flame

incidence with respect to the bridge wall may be varied or adjusted as desired.

Other objects and advantageous features of the invention will be apparent from the specification and claims.

The nature and characteristic features of the invention will be more readily understood from the following description taken in connection with the accompanying drawings forming part 10 hereof, in which:

Figure 1 is a vertical sectional view through a furnace in accordance with the present invention, and illustrating the construction and arrangement of the burner for gaseous fuel firing;

15 Fig. 2 is a vertical sectional view taken approximately on the line 2—2 of Fig. 1;

Fig. 3 is a horizontal sectional view taken approximately on the line 3—3 of Fig. 1;

Fig. 4 is a view similar to Fig. 1 and illustrating the arrangement of the burner for oil firing;

Fig. 5 is a vertical sectional view taken approximately on line 5—5 of Fig. 4, and

Fig. 6 is a top plan view of an oil burner which may be employed in connection with the furnace 25 of the present invention.

It should, of course, be understood, that the description and drawings herein are illustrative merely and that various modifications and changes can be made in the structure disclosed 30 without departing from the spirit of the invention.

Like numerals refer to like parts throughout the several views.

Referring now more particularly to the drawings, in which a preferred embodiment of the invention is illustrated, a furnace F is shown in part which includes a vertical front wall 10 and a vertical bridge wall 11 parallel to and spaced from the front wall 10. The wall 11 may be the 35 side or rear wall or the center wall of an up-draft heater or furnace of conventional type. One of the vertical end walls is illustrated at 12. The walls 10, 11, and 12 are made of suitable refractory material. The lowermost tubes, of a series 40 of tubes to be heated in the furnace, are shown at 14.

The furnace F is supported upon a foundation or horizontal floor 15, and, spaced upwardly therefrom, spaced horizontal walls 16 and 17 are provided. The wall 17 may serve as the lower boundary wall of the interior chamber of the furnace. In the space between the floor 15 and the wall 16, and extending forwardly from the wall 11, a plurality of vertically extending walls 45 18 are provided, for each burner location. The space 19, bounded by the floor 15, the walls 18

and the wall 16, constitutes a lower air duct, for purposes to be explained.

Similarly, in the space between the wall 16 and the wall 17, vertical walls 20 are provided for each burner location. The space 21 between the wall 16, the wall 17 and the walls 20, constitutes an upper air duct, for purposes to be explained.

It will, of course, be understood that the furnace, in accordance with its size, will be provided with a plurality of burner locations each including a pair of upper and lower air ducts, in the space between the end walls 12 thereof, although for purposes of explanation only one pair of ducts has been illustrated.

The horizontal wall 16 is provided, at the wall 15 11, with a burner block 25 of refractory material, supported by the wall 16, the walls 18, and the wall 11, one burner block 25 being employed for each lower air duct 19. Each burner block 25 has a central opening or throat 26, inclined from the 20 vertical, as illustrated in Figs. 1 and 3, and preferably at an angle of the order of 10° with respect to the wall 11. The opening or throat 26, as illustrated in Figs. 1 and 3, is flaring from the 25 lower to the upper ends to provide a flaring sheet-like flame pattern.

On the floor 15, in the lower air duct 19, a trackway is provided preferably comprising a channel section 27 mounted on a supporting plate 23 and fixedly secured to the floor 15. At the sides of the 30 lower portion of the lower air duct 19, a plurality of channels 24 is provided, having track plates 28, which extend into the walls 18, carried thereon. The plates 28 extend longitudinally in the air duct 19 and provide an additional trackway.

At the front end of the lower air duct 19, and carried by the front wall 10, a door 30 is provided, preferably pivotally mounted to permit of outward swinging, and having an adjustable damper 31 thereon for admission of primary air. At the 40 front end of the upper air duct 21, an air door 32 is provided, preferably pivotally mounted to permit of outward swinging and having an adjustable damper 33 thereon for the admission of secondary air to the duct 21.

The front wall 10, above the wall 11, may be 45 provided with a sight port 34, for observing combustion conditions in the furnace.

As illustrated in Figs. 1 and 2, a gas burner 35 is provided for each lower air duct 19, removably mounted therein, and is preferably an inspiring gas burner of conventional Venturi type, and in which from 40 to 100 per cent of the total air for combustion of gas, depending on the gas pressure, is drawn into a Venturi section 36. A gas supply pipe 37, preferably having a section 37a of flexible character, is provided and is connected to the Venturi section 36 at one end, an air inlet adjusting plate 38 being mounted on the Venturi section 36. The plate 38 is adapted to be positioned to determine the quantity of air admitted to the Venturi section 36, by a threaded rod 39, carried in a plate 40 mounted on the pipe 37, and capable of rotation by means of a handle 41, for adjusting the air. A handle 42 is also mounted on the gas supply pipe 37 for positioning the gas burner 35 in the duct 19.

The Venturi section 36 has, connected to the other end, a pipe nipple 43, of a length in accordance with the particular furnace, and on the outer end of the nipple 43, a manifold burner casing 44 is mounted and supported. The burner casing 44 preferably has lower flat wall portions 45 and a flat V-portion 46, for purposes to be explained.

On the upper end of the burner casing 44, a plurality of nozzles or burner tips 47 are mounted, preferably at an inclination corresponding to the angular disposition of the throat 26. The burner tips 47 with the throat 26 provide an approximately sheet-like flame.

On the innermost end of the manifold 44 a stop 48 is provided which is adapted to abut against the wall 11 for positioning the manifold 44 upon insertion in the lower air duct 19.

The gas burner 35 is supported, at the inner end thereof, by the engagement of the wall portions 45 and 46 with the track plates 28 and the trackway 27, and is further supported by a bracket 49 in engagement with the Venturi section 36 and with the trackway 27.

As illustrated in Figs. 4, 5 and 6, an oil burner 50 is provided for each lower air duct 19 and removably mounted therein. Each of the oil burners 50 preferably includes an oil supply pipe 51 having a flexible section 51a, connected to any suitable source of oil to be fired and to a manifold 52. A control valve 53 is provided in the supply pipe 51 for controlling the quantity of oil supplied.

A fluid connection 54 is provided, having a flexible section 54a, connected to a suitable source of atomizing fluid such as steam or air under pressure, and to the manifold 52. A control valve 55 is provided in the fluid connection 54 for controlling the quantity of atomizing fluid. The manifold 52 has a by-pass valve 56 therein. The manifold 52 has an oil delivery pipe 57 and an atomizing fluid delivery pipe 58 connected thereto, the other terminal ends of the pipes 57 and 58 being connected by swivel joints to a nozzle pipe 59, which carries an atomizing nozzle 60 on its upper end. The pipes 57 and 58 are preferably secured to suitable supports 61 and 62 which are slidable in the trackway provided by the channel 27. The support 62 is preferably provided with an upwardly extending plate 63 in which is carried a threaded adjusting rod 64. The rod 64 has a collar 65 in engagement with the nozzle pipe 59, and nuts 66 on the rod 64 permit of adjustment of the inclination of the nozzle pipe 59.

The nozzle pipe 59 is preferably adjusted to the desired angle of inclination and in conformity to the inclination of the throat 26 in the burner block 25, and is centered with respect thereto. The nozzle 60 and the throat are adapted to deliver a flaring sheet-like flame. The nozzle pipe 59 preferably has a bracket 67 secured thereto which is adapted to abut against the bridge wall 11 and serve as a stop for positioning the burner 50 upon insertion into the lower air duct 19.

Extending upwardly from the wall 17, at the rear end thereof, and substantially in alignment with the front of the throat 26, a screen wall or dam 70 is provided, parallel to the bridge wall 11, and preferably extending from one side wall 12 to the other side wall. The screen wall 70 is preferably made of refractory material and by deflecting upwardly any combustion gases falling within the furnace prevents the admixture thereof with the flame issuing from the throat 26. It will be noted that a trough 71 is provided in front of the rear wall 11, between the side walls 12, above the burner blocks 26, and to the rear of the rear ends of the air ducts 21 and of the screen wall 70.

The mode of operation will now be pointed out. When it is desired to supply heat to the furnace, 75 and particularly to heat the wall 11 for emitting

radiant heat, either of the burners 35 or 50 may be employed in accordance with operating conditions.

If it is desired to utilize oil for fuel, the oil burner 50 is inserted in the lower air duct 19 and slid along the trackway 27 until the stop 67 comes into engagement with the wall 11. The upper air duct 21 may be employed for ignition. Oil, supplied through the pipe 51 and atomizing fluid supplied through the pipe 54, are delivered to the nozzle pipe 59 for discharge from the nozzle 60 in a flat pattern. A part or all of the air required for combustion may be introduced through the lower air duct 19, by suitable adjustment of the damper 31 in the door 30, and, if desired, a part of the air for combustion may be supplied through the upper air duct 21, as determined by the positioning of the damper 33 in the door 32. The air entering the furnace through the upper air duct 21 mixes with the advancing stream passing from the throat 26.

If on the other hand, it is desired to heat the furnace with gas fuel, the oil burner 50 may be withdrawn by sliding the same outwardly along the trackway 27. The gas burner 35 may then be slid along the trackway 27 and the track plates 28 and to a position where the stop 48 engages the wall 11. Gas, supplied from the pipe 37 is delivered to the Venturi section 36 where air is inspirated in accordance with the positioning of the plate 38, and mixes with the gas for delivery to the casing 44 and the burner tips 47. The flame from the gas-air mixture discharged through the burner tips 47 passes upwardly through the throat 26. Air is admitted through the duct 19 in accordance with the positioning of the damper 31 for supplying the additional air as required for combustion of the gas-air mixture. If desired, also, air may be admitted through the upper air duct 21 as determined by the positioning of the damper 33 for aiding in the completion of combustion of the gas-air mixture.

The flame from the oil burner 50 or from the gas burner 35 is caused to impinge on the bridge wall 11, and thus radiates heat to the front wall absorption tubes 14. The hottest spot on the bridge wall 11 may be altered as to intensity and location by changing the angle of incidence of the flame to the bridge wall 11. This can be accomplished by raising the outside end of either the oil burner 50 or the gas burner 35, the flexible connections 51a and 37a permitting of this adjustment while the burners are in operation.

It will also be noted that the upper air duct 21, with its door 32, serves not only for the insertion of a lighting torch and for observation of the flame but that the door 32 is capable of functioning as an explosion relief door.

When the furnace is in operation, the flame and the bulk of the combustion gases impinge on and climb upwardly along the bridge wall 11, rise into the convection tube bank (not shown), and then pass into the stack. A small amount of the resultant spent gases may and often does descend within the furnace to cause a re-circulating effect. When this descending current of gas reaches the bottom of the furnace, which in the furnace shown comprises the upper surface of the wall 11, it would normally tend to mix with the flame. Since the descending gas is composed principally of carbon dioxide and nitrogen, these inert gaseous components tend to delay ignition and retard combustion, causing a longer and smoky flame and a higher stack temperature.

The wall or dam 70 prevents the mixing of the re-circulated inert gases with the flame until after sufficient air has been supplied thereto through the ducts 19 and 21 to insure quick and complete combustion, with a minimum of excess air. The trough 71 to the rear of the wall or dam 70 with a plurality of burners therealong aids in the ignition of the fuel and stabilizes the burning.

I claim:

1. In a furnace having vertical front, rear and side walls enclosing a furnace chamber, spaced walls at the lower portion of the furnace chamber providing a plurality of horizontally disposed inwardly extending upper and lower air ducts, a vertical screen wall extending from one side wall to the other side wall spaced forwardly from said rear wall and extending upwardly from said lower air ducts above said upper air ducts and into said furnace chamber to a height at least as great as the height of said upper air ducts to provide a transverse trough, said screen wall having openings therethrough for said upper air ducts, damper members for controlling the delivery of air into each of said ducts, a burner block between the inner ends of each of said lower ducts and said trough having an upwardly extending throat with a forwardly disposed wall portion parallel to the rear wall and a rearwardly disposed wall portion inclined at an angle with respect to said rear wall, and a burner retractably mounted in each of said lower ducts and having a discharge portion for alignment with said throat and said trough, said screen wall preventing the admixture of gases of combustion with the flame and with the air advancing upwardly from said ducts.
2. In a furnace having vertical front, rear and side walls enclosing a furnace chamber, spaced walls at the lower portion of the furnace chamber providing a plurality of horizontally disposed upper and lower air ducts, a vertical screen wall extending from one side wall to the other side wall spaced forwardly from said rear wall and extending upwardly from said lower air ducts above said upper air ducts and into said furnace chamber to a height at least as great as the height of said upper air ducts to provide a transverse trough, said screen wall having openings therethrough for said upper air ducts, members for controlling the delivery of air into each of said ducts, one of said spaced walls having an upwardly extending opening at the inner end of each of said lower ducts in communication with said trough, and a burner retractably mounted in each of said lower ducts and having a discharge portion for alignment with said upwardly extending opening and said trough, said screen wall preventing the admixture of gases of combustion with the flame and with the air advancing upwardly from said ducts.

WILLIAM FERGUSON.
